UNITED STATES PATENT OFFICE.

THOMAS WILLIAM ELDER, OF FORT WAYNE, INDIANA, ASSIGNOR TO VAN ARNAM MFG. CO., A CORPORATION OF INDIANA.

SHAPER-HEAD.

1,189,436.

Specification of Letters Patent.

Patented July 4, 1916.

Application filed April 19, 1916. Serial No. 92,230.

To all whom it may concern:

Be it known that I, THOMAS WILLIAM ELDER, a citizen of the United States of America, and resident of Fort Wayne, in the 5 county of Allen and State of Indiana, have invented certain new and useful Improvements in Shaper-Heads, of which the following is a specification.

This invention relates to improvements in 10 shaper heads of that class in which a number of bits are secured in connection with a revolving spindle with their respective cutting edges arranged equi-distant from the axis upon which the spindle revolves, 15 and the object of the improvement is to provide a construction for securing several pairs of bits in a common plane so that a greater number of cutting edges may be utilized in carrying out the operation of 20 the shaper-head upon the stock.

The object of the improvement is accomplished by the construction illustrated in the accompanying drawings in which:

Figure 1 is a plan view of the device including a complete set of bits secured therein; Fig. 2 is a bottom plan view of the intermediate block and cap associated together; Fig. 3 is a plan view of the base-plate; and Fig. 4 is a vertical section of the shaper-head, the spindle and securing nuts being 30 shown in full.

Similar characters of reference indicate corresponding parts throughout the several views and referring now to the same: 1 is 35 a rotatable spindle having a shoulder (2) thereon, and which has a threaded extension (3) beyond the shoulder.

4 is a base-plate circular in form and having a central opening (5) through which 40 the extension (3) of the spindle extends, the lower face of the plate being so formed about the opening as to fit snugly upon the shoulder (2). In the upper face of the plate are made parallel grooves (6) one upon 45 each side of the spindle opening, and also a second pair of parallel grooves, one upon each side of the opening and extending at right angles to the former grooves.

An intermediate block (8) having recesses 50 (9) made in its sides is mounted upon the extension of the spindle, the latter extending through the central opening (10) made in the former. In the bottom face of the intermediate block are made a pair of 55 grooves (11), one upon each side of its cen-

tral opening and extending at right angles to its recesses. A cap (12) is formed with a recess (13) in its under side and with pendant lugs (14) and (15) respectively, oppositely disposed and having in their 60 lower faces corresponding grooves (16) and (17) in parallel relation with each other. The pendant lugs are adapted to fit movably within the corresponding recesses in the intermediate block, the length of the 65 lugs being slightly greater than the thickness of the block. The recess (13) is of sufficient size as to contain without obstruction the lower nut (18) on the spindle, the former being for the purpose of clamping 70 the intermediate block (8) upon the bits (19) that are set between the block and the base-plate and within the corresponding grooves. A nut (20) on the spindle serves to clamp the cap (12) with its lugs bearing 75 upon the bits (21) that are inserted between the lugs and the base-plate in the corresponding grooves therein.

By means of this construction several pairs of bits are held in fixed relation in a common plane and with their respective cutting edges positioned so as to perform in common 80 the intended operation upon the stock.

A feature of the invention is the means for securing bits in independent pairs in 85 the same plane and with their cutting edges positioned for a common operation.

What I claim is:—

1. In a device of the class described, a revoluble spindle having a shoulder thereon 90 and threaded extension; a base-plate on the extension resting against the shoulder, the upper face of the plate having two pairs of parallel grooves extending at right angles to each other; an intermediate block upon 95 the extension having a pair of grooves made in its lower face; a pair of bits arranged between the base-plate and block, their edges extending into the corresponding grooves therein, said block having also a 100 recess in each side; a nut on the extension for clamping the intermediate block against said bits; a cap having a recess to accommodate the nut, and also pendant lugs adapted to fit loosely in the recesses in the 105 intermediate block, each lug having a groove made in its lower face; a second pair of bits arranged between the lugs on the cap and the base-plate with their edges extending in the corresponding grooves; 110

and a nut on the spindle for clamping the cap upon the latter bits.

2. In a device of the class described, a rotatable spindle; a base-plate thereon having two pairs of parallel grooves in its upper face arranged at right angles to each other; two pairs of bits arranged with their lower edges in the corresponding pairs of grooves and with their cutting edges positioned respectively at points equi-distant from the axial center of the spindle; and means in connection with the spindle for independently clamping each pair of bits in position upon the base-plate.

15 3. In combination with a rotating spindle, a base-plate mounted thereon; an intermediate block mounted upon the spindle having a recess in each side thereof; a pair

of bits arranged between the base-plate and block in parallel relation with each other, 20 one upon each side of the spindle; means on the spindle for clamping the block upon the bits; a cap having pendant lugs extending through the recesses in the block respectively; a second pair of bits arranged 25 in parallel relation with each other and at right angles to the former bits; and means for clamping the cap to hold the latter bits between said lugs and base-plate.

In testimony whereof I affix my signature, in presence of two witnesses.

THOMAS WILLIAM ELDER.
